UNITED STATES PATENT OFFICE.

DELLWIN S. GRAHAM, OF DAVENPORT, IOWA.

OPTICAL ATTACHMENT FOR PLAYER-PIANOS.

1,355,469.

Specification of Letters Patent.

Patented Oct. 12, 1920.

Application filed January 22, 1918. Serial No. 272,408.

To all whom it may concern:

Be it known that I, DELLWIN S. GRAHAM, a citizen of the United States, residing at Davenport, in the county of Scott and State 5 of Iowa, have invented certain new and useful Improvements in Optical Attachments for Player-Pianos, of which the following is a specification.

This invention relates to improvements in 10 player-pianos and it has for its object providing means for making conveniently visible any characters or words which it is desired to have accompany the notes which the player-pianos are producing.

15 It is customary with player-pianos for the paper record to be mounted on rolls and to be moved downwardly across the tracker-bar of the player-piano, the perforations in the record, as is well known, operating, by 20 pneumatic means, the various notes of the piano. It is often desired to see the characters which represent the notes which are being played, and also to have words of the 25 music conveniently placed. When the notes or words are printed on the paper record, parallel with the series of perforations, and thus moving vertically with the perforations, it is difficult to read the notes or the 30 words, not only because of the vertical direction of movement, but also because it is necessary to read relatively upwardly instead of downwardly. The purpose of my 35 invention is to eliminate these disadvantages by producing images of the notes or words, which are conveniently placed, and are of such forms and dimensions as are most suitable for the use of the operator of the player-piano or others. Other objects of the 40 invention will be apparent from a consideration of the accompanying drawings and the following description thereof.

Figure 1 is a plan view of apparatus which illustrates the features of my invention. Fig. 2 is an elevation, of the same. 45 Fig. 3 is a section along the line 3—3 of Fig. 2. And Fig. 4 is a fragmental view of a paper record which may be used with the player-piano in conjunction with the apparatus.

50 Although I have herein illustrated and described the form and arrangement of apparatus which I prefer for the purpose of illustrating my invention, yet it is to be understood that many modifications may be 55 made therein, by those skilled in the art, without departing from the spirit of my

invention, as set forth hereinafter by the claims.

Without illustrating to any material extent the elements of the player-piano, it is 60 to be understood that the paper record 8 of the player is caused, by suitable rollers 9 and 10, to move downwardly along the tracker-bar 11, perforations 12 opening at the proper time the air ports 13 of the tracker-bar. As is indicated in Fig. 4, characters, 65 which represent the notes 14 which are being played by the player-piano, are printed on the record parallel with the rows of perforations, and pass down over the tracker-bar 70 as indicated. It is desired to produce an image of these notes that may be conveniently seen by the operator. To accomplish this I use a plurality of mirrors, suitably mounted and arranged so as to form, by a 75 series of reflections from the various reflecting surfaces of the mirrors suitable images. The light passes from the notes 14 to the mirror 15, the surface of which is arranged, for the purpose of illustration, substantially 80 vertically, but which forms an angle of substantially 45° with the plane of the paper record. The light passes from this mirror to a mirror 16, the reflecting surface of which, in this instance, is inclined at an angle of 85 substantially 45° with the horizontal, with its plane, however, being substantially at right angles to the record. Light then passes from this mirror to mirror 17, which is arranged horizontally, but with its plane 90 forming more or less of an angle with the record, so that the images of the notes formed thereby may be conveniently viewed by the operator. By this arrangement not only are images formed in a convenient position to be viewed; but, as, is hereinafter 95 described, by properly curving some, or all of the mirrors, the shapes of the images may be distorted with reference to the originals, so as to produce any desired effect. 100

Any suitable apparatus may be used for mounting the mirrors and for conveniently adjusting the same for various purposes. I prefer for the purpose an arm 20 suitably attached to some portion of the player piano. 105 I prefer to have it removably attached by means of the clamp 21, to the projecting end of the tracker-bar 11. For the purpose of removably attaching the arm I prefer short pins 22, which are fixed to the clamp 110 and which pass freely through corresponding openings in the arm. By unscrewing

sufficiently the set screw 40, the arm 20 can be lifted off from the pins 22 and removed from the tracker-bar. At the outer end of the arm 20 the mirror 15 is pivoted in any 5 suitable manner, for instance by means of the pivot 23 fixed to the arm, and the bracket 24 fixed to the mirror. By means of the set screw 25 the mirror may be set in the proper position with reference to the 10 characters that are to be reflected and the remainder of the apparatus.

Also fixed to the outer end of the arm 20 is a bracket 26, which is arranged to support, by an arm 27, the mirror 16 by means 15 of the bracket 28 and the pivot 29. A second arm 30 also projects from the bracket 26 and is arranged to support the mirror 17. This mirror may be pivotally supported by the arm in a manner similar to that of the 20 other mirrors, or it, or either of the other mirrors, may be supported by a universal joint. In this instance I prefer to support the mirror 17 by the universal joint 31 shown in Fig. 3. In order to more conveniently 25 make adjustments, any suitable friction means may be provided for any of the mirrors, so that the mirrors may be readily rotated to the position desired and will then be held in place without loosening 30 or tightening the set screws. I prefer for this purpose a friction device comprising a shoe 32 backed by a spring 33, the compressive force of the spring being varied by means of the screw 25.

35 By the use of this apparatus it will be seen that, by suitably adjusting the mirrors on the pivots, the light from the characters can be reflected properly so as to be cast outwardly from mirror 17 in any suitable direction. The mirrors themselves may be supported by any suitable backs; and the entire apparatus, particularly the backs of the mirrors themselves, may be finished in any suitable manner and by the use of any 45 suitable substance, such as wood, plush, or the like.

Also the reflecting surfaces of the mirrors may be plane or curved, as may be desired to meet the needs or the views of users. In 50asmuch as, by the use of the characters printed on the paper record, it is necessary to spread the characters out somewhat abnormally in a vertical direction, I prefer to have the mirror 16 longitudinally somewhat 55 concave and cylindrical in shape. Thus as the images are reflected from this mirror they will be condensed somewhat longitudinally which is equivalent to condensing the characters themselves vertically; so that the 60 abnormal separation of the characters apparently disappears. Also, as, frequently, it may be desired to crowd the characters together somewhat horizontally because of lack of space on the paper record, or otherwise, I prefer to have the reflecting surface 65

of the mirror 17 longitudinally more or less convex so as to extend the images somewhat vertically, which corresponds to a horizontal extension of the actual characters. It is evident that, by providing suitable curvature 70 for the various mirrors, the amount of the distortion of the images may be made as great or as little as may be desired; or it may be entirely eliminated by the use of plane mirrors; and other means may be used 75 for producing distortions such as the curvature of mirror 15; or, if diminishing or enlarging of the entire characters is desired, convex or concave spherical mirrors may be 80 used.

In order to indicate to the observer the particular notes as they are being played, or the words which are to accompany such notes, I provide a pointer 35, which is held adjacent the paper record in any suitable 85 manner; for example by means of a bar 36, slidably mounted on the back of the mirror 15 by means of clips 37, and set in place by means of a set screw 38. The image of this pointer projected by the mirror 17 will thus be adjacent the images of the notes or words as they are being played. A second pointer 35, (Fig. 2) may be used, if desired, in order to indicate not only the proper notes or words, but also the length of the notes, the 90 distance between the pointers representing a certain time length. This would serve for various purposes, for instance, a pupil would thus be aided in counting time correctly. 95

I claim as my invention:

1. In a player-piano, a paper record having characters printed thereon and arranged to be moved downwardly, in combination with means for producing conveniently visible images of said characters; said means comprising a first mirror mounted adjacent said characters, and arranged to receive light therefrom and to reflect said light substantially horizontally and substantially parallel with the plane of said record, a second mirror mounted adjacent said first mirror and arranged to receive the said reflected light from said first mirror and to reflect said light downwardly; and a third mirror mounted beneath said second mirror arranged to receive said reflected light from said second mirror and to reflect said light upwardly to a position conveniently visible by the operator of the player piano; said mirrors being pivotally mounted for convenient and rapid adjustment, and said second mirror having a cylindrical concave reflecting surface, and said third mirror having a cylindrical convex reflecting surface. 105 110 115

2. In a player-piano, a paper record having characters printed thereon, and arranged to be moved downwardly, in combination with means for producing conveniently visible images of said characters; said 120 125 130

- means comprising a first mirror mounted adjacent said characters, and arranged to receive light therefrom and to reflect said light substantially horizontally and substantially parallel with the plane of said record, a second mirror mounted adjacent said first mirror and arranged to receive the said reflected light from said first mirror and to reflect said light downwardly; and a third mirror mounted beneath said second mirror arranged to receive said reflected light from said second mirror and to reflect said light upwardly to a position conveniently visible by the operator of the player-piano; said second mirror having a cylindrical concave reflecting surface, and said third mirror having a cylindrical convex reflecting surface.
3. In a player-piano, a paper record having characters printed thereon, and arranged to be moved downwardly, in combination with means for producing conveniently visible images of said characters; said means comprising a first mirror mounted adjacent said characters and arranged to receive light therefrom and to reflect said light substantially horizontally and substantially parallel with the plane of said record, a second mirror mounted adjacent said first mirror and arranged to receive the said reflected light from said first mirror and to reflect said light downwardly; and a third mirror mounted beneath said second mirror arranged to receive said reflected light from said second mirror and to reflect said light upwardly to a position conveniently visible by the operator of the player-piano.
4. In a player-piano, a paper record having characters printed thereon, and arranged to be moved downwardly, in combination with means for producing conveniently visible images of said characters; said means comprising a first mirror mounted adjacent said characters and arranged to receive light therefrom and to reflect said light substantially horizontally and substantially parallel with the plane of said record, a second mirror mounted adjacent said first mirror and arranged to receive the said reflected light from said first mirror and to reflect said light downwardly; and a third mirror mounted beneath said second mirror and arranged to receive said reflected light from said second mirror and to reflect said light upwardly to a position conveniently visible by the operator of the player piano.
5. In a player-piano, a paper record having characters printed thereon, and arranged to be moved downwardly, in combination with means for producing conveniently visible images of said characters; said means comprising a first mirror mounted adjacent said characters, and arranged to receive light therefrom and to reflect said light substantially horizontally and substantially parallel with the plane of said record, a second mirror mounted adjacent said first mirror and arranged to receive the said reflected light from said first mirror and to reflect said light upwardly to a position conveniently visible by the operator of the player-piano, one of said mirrors having a curved surface.
6. In a player piano, a paper record having characters printed thereon arranged to be moved, in combination with means for producing visible images of said characters; said means comprising a first mirror arranged to receive light from said record adjacent said characters and to reflect said light substantially at right angles to the direction of movement of said record, and substantially parallel with the plane of said record, a second mirror mounted and arranged to receive the said reflected light from said first mirror and to reflect said light substantially in the direction of motion of said record, and a third mirror mounted beneath said second mirror and arranged to receive said reflected light from said second mirror and to reflect said light to a position conveniently visible by the operator of the player piano.

In testimony whereof, I hereunto set my hand.

DELLWIN S. GRAHAM.
